SHOE LAST

Felix De Vito, Brooklyn, N. Y.

Application March 31, 1945, Serial No. 585,880

5 Claims. (Cl. 12—135)

The present invention relates to a shoe last, and more particularly to a two-piece expandible last.

The object of the present invention is to provide a two-piece last which may be extended and retracted for stretching the uppers of pumps, slippers or the like, preparatory to the manufacture of the finished shoe.

Another object of the invention is to provide a two-piece last which will be strong enough when extended to withstand the abuse and high pressure encountered in the several subsequent operations the last must undergo before the finished shoe is produced.

Other objects and advantages of the present invention will be obvious as brought out in the following specification.

Reference will be had to the accompanying drawing forming a part of this specification in which similar reference characters indicate corresponding parts throughout the several views, in which—

Figure 1 is a top plan view of a two-piece last closed;

Fig. 2 is a side view with a broken away portion;

Fig. 3 is a bottom view of the last with a broken away portion viewed in the direction of the arrows 3—3 of Fig. 2;

Fig. 4 is a side view of the last closed, showing the upper nailed to the bottom of the last;

Fig. 5 is a view similar to Fig. 4 showing the last in the extended position stretching the upper;

Fig. 6 is a fragmentary detail of the cam mechanism positioned when the last is closed;

Fig. 7 is a fragmentary detail of the cam mechanism when the last is open;

Fig. 8 is a side view of the key for turning the cam; and

Fig. 9 is a perspective view of the cam.

Referring to the drawing, wherein I have shown, by way of illustration merely, a two-piece shoe last comprising a heel portion 10 and a toe or fore portion 11, separated at 12, to form two flat surfaces 13 and 14.

Secured to the surfaces 13 and 14 are a pair of plates 15 and 16 resting in recesses 17 and 18. The plates 15 and 16 are provided with semi-annular grooves 19 and 20 to accommodate the cylindrical cam 21 as best shown in Fig. 6.

The cylindrical cam is provided with a pair of integral fins 23 and 24 diametrically opposed on each side of the cylinder, and adapted to ride in the grooves 19 and 20 for separating the two-piece last as hereinafter explained.

The heel portion 10 and the toe or fore portion 11 are normally held together by dowel pins 25 which are fixed tightly in the recesses 26 of the toe portion 11; but are free to move in the recesses 27 of the heel portion 10.

The heel portion 10 and toe portion 11 are again supported by a pair of metal straps 60 and 61 secured by pins 62 and 63 running through the last adjacent the top thereof. The pin 63 passes through a slot 64 in each strap 60 and 61 to allow for the separating movement of the heel and toe portion.

Since there is considerable pressure on the toe and heel portions in the direction of the arrows 15 A—A in Fig. 4, when the last is placed upon a conveyor, the metal straps 60 and 61 are embedded in the side of the last so that the part of the last indicated at 65 acts as a support for the straps and prevents any rotational movement 20 of the toe portion in respect to the heel portion.

It is well to mention here that lasts having only dowel pins for support are absolutely useless when subjected to pressure during the operations imposed upon them, and frequently break in half.

25 On the top surface of the last there is provided a socket 31 in the heel portion and socket 66 in the toe portion. The socket 31 is used for applying the last to a pin for some of the subsequent operations, and the socket 66 is used for assisting 30 the removal of the last from the finished shoe.

A coil spring 35 is mounted in a recess 36 and 37 in the heel portion 10 and toe portion 11, and secured to each portion respectively by screws 38 and 39. The coil spring 35 is at rest when the last is closed and assists in closing the last when the last is expanded.

The cylindrical cam 21 has a square extension 40 adapted to receive the socket of a key socket wrench 41 for rotating the cam for opening and 40 closing the last.

In using the last for manufacturing shoes, the upper 50 is placed over the last when the last is closed or retracted as shown in Fig. 4, and since the last in its closed position is much smaller than 45 the shoe size to be produced when the last is extended, the operator can very easily nail the toe portion of the upper to the bottom of the last at substantially four places as shown in Fig. 3.

After the upper is nailed to the last the operator places the key 41 over the extension 40 of the cam 21 and turns the key one-quarter of a turn in either direction to extend or separate the last as shown in Figs. 5 and 7.

When the upper is stretched the edge 51 completely hugs the contour of the last, and after the

last is separated the several subsequent operations are performed to produce the finished shoe while the last is in the extended position. Consequently, when the shoe is finished the part 51 of the upper 50 will fit snugly around the foot of the wearer.

It will be understood that the present invention has been made primarily to manufacture pumps so that when the shoe is finished the sides of the pumps will fit snugly against the foot of the wearer.

It has been found that with the present method of making pumps, whereby an ordinary last was used, it was necessary to subject the upper to a conventional stretching machine.

The present invention stretches the upper and eliminates the use of a stretching machine; but since the last is in two pieces, there is danger of breakage, and the novel features of the present invention overcome this difficulty.

Many other uses may be had from this last without departing from the spirit of the invention.

I claim:

1. A device of the kind described comprising, a last having a heel portion, a fore or toe portion separating on a vertical line at right angles to the longitudinal axis of the last to form two abutting surfaces, a plate secured to each abutting surface having semi-annular grooves therein, a cylindrical cam having diametrically opposed fins thereon adapted to ride within the aforesaid semi-annular grooves in said plates to separate said heel and toe portion of said last, means comprising said annular grooves for accommodating a portion of said cylindrical cam when said last is closed, a square extension on said cam adapted to receive a key for rotating said cam, spring means for assisting the closing of said last, dowel pins for guiding said last longitudinally, and metal straps mounted on each side of said last adjacent the top thereof to prevent any rotational movement of said heel portion relative to said toe portion.

2. A two-piece expandible last comprising a heel portion, a toe or fore portion, means comprising a cylindrical cam for extending said last, a spring for retracting said last, dowel pins for guiding said heel portion and said toe or fore portion longitudinally, and means comprising metal straps for preventing any rotational movement of one portion to the other.

3. A device of the kind described comprising,

an expandible two-piece last having a heel portion, a toe or fore portion, both of which separate on a vertical line at right angles to the longitudinal axis of the last thereby forming two abutting surfaces, a longitudinal plate secured in recesses in each abutting surface and having semi-annular grooves therein running the entire length of said plates, a cylindrical cam having diametrically opposed fins thereon and adapted to rotate within said semi-annular grooves in said plates to separate said heel portion from said toe or fore portion of said last, means comprising said annular grooves for accommodating a portion of said cylindrical cam when said last is closed, a square extension on said cam adapted to be rotated by a key for opening and closing said last, spring means for assisting the closing of said last embedded and secured in recesses in the toe and heel portion thereof, a pair of dowel pins embedded in recesses of the heel and toe portion of said last with one end fixed and the other end free to move for guiding said heel and toe portion longitudinally thereof, a cylindrical socket in said heel portion adjacent the top thereof, a second socket in the toe or fore portion adjacent the top thereof, and means comprising a metal strap embedded on each side of said last having one of its ends fixed to the toe portion of said last and the other end free to move around a pin in said heel portion of said last to prevent any rotation movement of said heel portion relative to said toe portion.

4. A two-piece expandible last comprising, a heel portion, a toe or fore portion separating on a line substantially vertical to the longitudinal axis of said last, cam means mounted between the dividing line of each portion for separating said last, spring means for assisting the closing of said last, dowel pins for guiding said portions longitudinally, and metallic straps for preventing any rotational movement of the heel portion relative to said toe or fore portion.

5. A two-piece expandible last comprising a heel portion, a toe portion, means for opening and closing said last, means for guiding said last, and means comprising metallic straps permanently fixed to one portion of said last and movably fixed to the other portion of said last for preventing any rotational movement of one portion of said last relative to the other portion of said last.

FELIX DE VITO.
